HYPODERMIC SYRINGE

Samuel James Everett, Thornton Heath,
EnglandApplication February 3, 1932, Serial No. 590,740
In Great Britain May 4, 1931

2 Claims. (Cl. 128—221)

This invention comprises improvements in hypodermic syringes and in interchangeable needles for use therewith, said syringes being provided with means for securing a needle head-piece to the nozzle part of the syringe.

One object of this invention is to provide an inexpensive and simple needle-mounting arrangement whereby a satisfactory tight joint between the needle and syringe and adequate support for the needle are ensured. A further object of the invention is to provide a needle-mounting arrangement which permits of the satisfactory bending of needles by the user to suit particular purposes. A third object is to avoid contaminatory contact between the needle and nozzle part or clamping part of the syringe during insertion or removal of a needle.

Various embodiments of the invention will now be described by way of example with reference to the accompanying drawings, in which: Figure 1 is a longitudinal section of one embodiment of syringe and needle, Figure 2 a longitudinal section, at right angles to Figure 1, of a clamping nipple, Figures 3 and 4 are elevations of alternative embodiments, Figure 5 is an elevation of a bent needle, Figures 6—8 are longitudinal sections of modified forms of needle, Figures 9 and 10 are front and side elevations of an alternative form of clamping nipple.

Referring to Figures 1 and 2, the hypodermic needle 1 is provided at its blunt end with a mounting of plastic metal, such as pewter, consisting of a head portion 2 and an elongated neck portion 3 of less diameter than said head portion. A substantial length of the needle 1 is permanently embedded in the mounting which is preferably formed upon and attached to said needle by a die casting, die pressing or like operation. The head 2 is shaped to fit in a complementary lodgement or cavity 4 in a nipple 5 which is internally threaded to screw on an externally threaded nozzle part 6. Said head, moreover, presents a bevelled shoulder 7 designed to lodge firmly in the lower part of the cavity 4 and a conical upper portion 8 for abutting against the flat lower end-face 9 of the nozzle 6. To permit of insertion of the needle 1 and mounting 2, 3, the nipple 5 has a lateral aperture consisting of a circular orifice 10 sufficiently large to pass the head 2 and a slot 11 sufficiently wide to pass the neck 3 into a throat 11' below the cavity 4. To mount a needle 1 on a syringe nozzle 6, the mounting 2, 3 is inserted laterally in the aperture 10, 11, the nipple 5 being in such a position that the nozzle face 9 is clear of the orifice 10.

The head 2 is then moved longitudinally into the cavity 4. The slot 11 being of less size than the diameter of the head 2, said head finds a firm lodgement in the cavity 4. The nipple 5 is then screwed on to the nozzle 6 until the upper portion 8 of the head is tightly clamped against the nozzle face 9. Owing to the plasticity of the mounting, a perfectly liquid tight joint is obtained. Instead of being flat, the nozzle face 9 may be conically recessed.

As will be seen, the blunt end of the needle does not come right through to the upper end of the mounting, but has its canula extended by a passage 12 in the mounting, said passage flaring upwardly from said canula to the bore 13 of the nozzle 6. If the mounting is die-cast, this flared passage 12 can be produced by inserting a removable tapered core in the blunt end of the needle and casting the mounting around this. Said flared passage facilitates the insertion in the needle of a wire for cleaning the same in well known manner.

As the canula of the needle, extended by the passage 12, communicates directly with the bore 13 of the nozzle 6, there will be no loss of the injected liquid such as is occasioned in arrangements wherein said canula and bore open into opposite sides of an intermediate cavity. Accurate dosage is thus ensured.

As shown in Figure 1, the nozzle 6 takes the form of an adaptor internally threaded at 14 so that it can be screwed upon a syringe of existing type to adapt the latter for use with needles 1—3 such as have been described. Such adaptors will be comparatively accurately made to ensure a liquid tight joint with the syringe and to prevent loss of injection liquid. Alternatively the nozzle may form an integral or permanent component of the syringe as shown at 6' in Figures 3 and 4.

Figure 3 illustrates an arrangement embodying a double-ended needle 1' for use with a cartridge or phial syringe, such as a so-called Cook's type syringe. A mounting 2, 3 similar to that just described is attached to the needle 1' at a point between its two sharp ends. To allow of the lateral insertion of the upper part of the needle 1', the nipple 5 is slotted at 15 and the nozzle 6' at 16 whilst the lower part 17 of the syringe body or cartridge container is rather more widely slotted at 18. A cartridge 19 and end closure 20 are indicated diagrammatically. The mounting 2, 3 is clamped in position as in the previous example and the syringe can then be employed in the usual fashion.

In Figure 4 the head and neck portions 2, 3 of the mounting are of slightly modified shapes, the aperture 10, 11 and the lodgement 4 being, accordingly, also somewhat modified. The liquid tight joint is, moreover, obtained in a different fashion: The upper end of the head 2 is flat and contacts with the flat end face 9 of the syringe nozzle 6'. The needle 1 extends right through the mounting and a projecting portion 21 extends 10 into the bore 13' of the nozzle. This arrangement also gives a good liquid-tight joint.

With such a mounting, wherein the needle 1 is tightly embedded in the neck 3, it is a simple matter to bend the needle in said neck to any angle (Figure 5) required for difficult injection operations such as arise, more particularly, in dental practice. Moreover, the needle retains the bent or curved shape which it is thereby given. Even hard needles can be bent in such mountings 20 in spite of the danger that they may break when bent: For since the needle is embedded in the mounting, a liquid tight joint is maintained in the event of such breakage whilst a lumen through the needle is still secured.

As will be observed, all the modifications described have the advantage that the needle 1 can be mounted on the syringe without it being necessary to pass the needle point through any narrow bore or orifice which might contaminate said point. Similarly the needle can be removed without contaminating the syringe or nipple. Consequently a surgeon making many injections, particularly in cases of emergency, can initially sterilize the syringe, insert a needle and make an injection, remove the needle without contaminating the syringe, insert a fresh sterile needle and make a further injection in a perfectly aseptic manner, repeating the operation as often as may be desired without any necessity for re-sterilizing the syringe itself. In the case of a double ended needle 1' (Figure 3) the pointed end of the needle which enters the syringe can also be inserted laterally, through the wide slot 18, without contamination. Thus a sterile cartridge or phial and a sterile needle may be used for each operation without the necessity of sterilizing the syringe before each such operation.

Furthermore, the rigid and secure manner in which the needle is held obviates any possibility of the needle wobbling or slipping and permits of very accurate incision. No loss of rigidity is experienced where a needle is bent as in Figure 5. Finally a good liquid-tight connection is made between the needle and syringe, escape of the injection liquid and inaccurate dosage being thereby prevented. Moreover the nipple and the syringe nozzle and butt remain clean so that there is little risk of contamination in this way.

For some purposes, for example where it is not 60 of essential importance that the needle should be capable of being bent, it may be preferred to make the mounting of harder metal, such as brass, and to provide it, at the end seating against the nozzle-face 9, with a facing or washer of softer plastic metal such as pewter. Two forms of such needle are shown in Figures 6 and 7. In Figure 6 the needle proper 1 extends up into the facing 22 of plastic metal, whereas in Figure 7 it only extends a part of the way into the neck portion 3 of the mounting. In another modification (Figure 8), the head portion 2 of a plastic metal mounting is encased in a shell 23 of harder metal.

In place of the screw connection shown in Figures 1-4 for securing the nipple 5 to the nozzle 6, 6' which is preferred for practical reasons, it

would naturally be possible to use other well known devices for bringing one part tightly against another. For example, the nipple might be engaged by toggle or cam means on the syringe body. An arrangement of the latter type is shown in Figures 9 and 10. In this arrangement, a stirrup shaped member 25 having its inturned ends 26 pivotally mounted in the nozzle 6 is bent to form a pair of shoulders 27 arranged to engage under an annular abutment 28 provided on the 10 nipple 5'. The inturned ends 26 pass through slots 30 in the nipple. If the member 25 is turned down to the left in Figure 9, it leaves the nipple free to be lowered to allow of the lateral insertion of the head portion of a needle mounting through the aperture 10. On turning the member 25 back into the position shown in Figures 9 and 10, the nipple 5' is raised by the camming action of the member 25 on the abutment 28, the seating face of the mounting being thereby forced tightly 20 against the end of the nozzle 6. Owing to the slight resultant crushing at said seating face and to the fact that the abutment 28 bears flat on the substantially horizontal shoulders 27, the arrangement is practically self-locking.

25

I claim.

1. In a hypodermic syringe, a nozzle, an interchangeable needle mounting having an axial passage therethrough, said mounting comprising a cylindrical head portion and a slender neck portion of plastic metal extending from said head portion and embedding the needle over a substantial portion of its length, said head portion being formed with an end face adapted for sealing engagement with said nozzle and having a shoulder 35 at the other end surrounding said neck portion, a clamping nipple adjustably secured to said nozzle having an axially disposed cylindrical cavity formed therein sized to fit said head and having a seat formed at the bottom thereof for said shoulder, said nipple having a lateral orifice above said cavity large enough to pass the head portion of said mounting laterally, and having a slot which extends from said orifice to the extremity of said nipple and is in lateral communication 45 with said cavity, said slot being smaller than said orifice and large enough to pass only the slender neck portion of said mounting laterally, whereby said head portion must be moved axially into position in said cavity after being passed laterally 50 through said orifice and the walls of said cavity will afford lateral support for said head portion to hold the needle mounting firmly in position during bending of the protruding portion of the needle and use of the syringe.

55

2. In a hypodermic syringe, a nozzle, a double ended needle, a mounting for said needle in which the latter is embedded intermediate its ends, said mounting comprising a cylindrical head portion and a slender neck portion of plastic metal extending from said head portion toward one end of the needle, said head portion being formed with an end face adapted for sealing engagement with said nozzle and having a shoulder at the other end surrounding said neck portion, a clamping nipple 65 adjustably secured to said nozzle having an axially disposed cylindrical cavity formed therein sized to fit said head and having a seat formed at the bottom thereof for said shoulder, said nipple having a lateral orifice above said cavity large enough 70 to pass the head portion of said mounting laterally, and having a slot which extends from said orifice to one extremity of said nipple and is in lateral communication with said cavity, said slot being smaller than said orifice and large enough 75

5 to pass only the slender neck portion of said mounting laterally, said nipple having a second slot extending longitudinally from said orifice to the other end of the nipple and large enough to pass the other end of the needle laterally, whereby said head portion must be moved axially into position in said cavity after being passed laterally

through said orifice and the walls of said cavity will afford lateral support for said head portion to hold the needle mounting firmly in position during bending of the protruding portion of the needle and use of the syringe.
